BARRETTE

Filed Jan. 24, 1930

UNITED STATES PATENT OFFICE

JOHN B. RICHARD, OF LEOMINSTER, MASSACHUSETTS, ASSIGNOR TO DU PONT VISCOLOID COMPANY, OF WILMINGTON, DELAWARE, A CORPORATION OF DELAWARE

BARRETTE

Application filed January 24, 1930. Serial No. 423,047.

This invention relates to barrettes, and more particularly to comb barrettes, that is, barrettes of the type not only providing clasp-
ing means for the hair but also including a
5 comb-like portion. One object of the invention is to provide a barrette of the general character indicated which may be inexpensively and rapidly manufactured from materials of the general type of cellulose ester
10 plastic such as cellulose nitrate, or cellulose acetate, plastic. A further object is to provide a barrette comprising a body portion carrying comb teeth and a cooperating clamp-
ing member for clamping the hair against
15 the body and between the comb teeth. To these ends, and also to improve generally upon devices of the character indicated, my invention consists of the various matters hereinafter described and claimed.

20 Without restricting the invention thereto, it is described with more particular reference to the embodiment thereof illustrated in the accompanying drawings. In these drawings: Figure 1 is a side elevation of a barrette with the clamping member thereof released to permit introduction of the hair into the barrette; Figure 2 is a similar view with the clamping member in clamping position; Figure 3 is a bottom view looking in the di-
25 rection of the arrow "3" in Figure 2; Figure 4 is a fragmentary enlarged edge view of the body with a portion broken away to show the manner in which the teeth may be affixed to the body; Figure 5 is a sectional view on line 5—5 of Figure 4; Figure 6 is a fragmentary enlarged view of the free end of the clamping member, looking in the direction of the arrow "6" in Figure 1; and Figure 7 is an enlarged end view of the body member 30 looking in the direction of the arrow "7" in Figure 1.

Referring now in detail to the drawings, the illustrated barrette comprises, in general, a body member 1 and a clamping member 2 hinged to the body portion at one end 3 and adapted for fastened connection with the body portion at the other end 4. The body portion 1 carries a comb, or series of teeth, 5 extending therealong, and the clamping member 2 is provided with a corresponding

longitudinal aperture, or slot, 6 for the reception of the teeth when the clamping member is in closed position. In use, the hair is laid over the body portion and between the teeth, and the clamping member is closed 55 into close cooperation with the body member and hair; and it will be noted that, in practical effect, the hair is held tightly against the body at one side of the comb, is woven over the bases of the teeth and between 60 the teeth, and is held tightly between the body and the clamping member at the other side of the comb.

In detail, and as illustrated, the body portion 1 and the clamping member, or tongue, 2 are given closely comparable curvatures, insuring a close cooperation between them. The tongue may be hinged to the barrette in any convenient manner, and there is shown a hinge comprising mated standards 7, 7 70 permanently connected with the body portion, as by being integral therewith or cemented thereto, the standards carrying a pintle 8 received in the end 3 of the tongue 2. For fastening the tongue to the body portion, while any suitable means may be provided, I have found the illustrated construction desirable.

In this construction the end 9 of the body is upturned and bifurcated as illustrated at 10 80 in Fig. 7, thus forming the sockets 11, 11 for the reception of the end 4 of the tongue. The rounded sides of the tongue have a snap-fit down between the rounded ends 10a, 10a of the end 9 as shown in Fig. 3, the resiliency 85 of the material permitting this.

In order to bring the tongue, when in closed position, in close cooperation with the body substantially throughout the entire length of the tongue, the tongue adjacent its 90 hinged end is provided with a downset 12, as distinguished from merely giving the tongue a uniform curve from the hinge pintle throughout the length of the tongue. The comb portion 5 carried by the body may be 95 connected therewith in any desired manner, but for convenience of manufacture the comb is desirably produced as a separate item from the body and then connected with the same; and as illustrated the body is provided with 100

a groove 13 (Figs. 4 and 5) into which the comb is inserted, and permanently held by, say, a suitable cement or by heat-fusion of the materials.

5 As indicated previously, the material of the barrette is desirably cellulose ester plastic of any suitable composition as (parts by weight) pyroxylin 23.6, camphor 7.5, urea .1, pigment (zinc oxide) 1, residual solvent 10 (alcohol) .3. With material of this general type the parts may be readily cut from sheet stock, and then given desired form and curvature, by heating either dry or wet, to, say, 190° F. for a short time to soften the 15 same, and then shaped. Also, such material gives a desired slight resiliency to the entire barrette and, in particular, provides the desired resiliency at the fastening 9.

Having thus described my invention, I 20 claim:

1. In a barrette, a body carrying comb teeth therealong, a tongue for cooperation with the body and provided with a slot for reception of the comb teeth, a hinge structure connecting the tongue with the body at one end, and a fastening means for the tongue and body at the other end, said body being upturned at such end to present said fastening means.

2. In a barrette, a body member carrying comb teeth therealong, a tongue member for cooperation with the body and provided with a slot for reception of the comb teeth, a hinge structure connecting the tongue member with the body member at one end, and a fastening means for the tongue member and body at the other end, such fastening means comprising an upturned end portion of said body to thereby present a spaced-standard structure 35 on the body for reception of the other member, the immediately cooperating parts presenting a shank-and-socket structure.

3. In a barrette, a body carrying comb teeth therealong, a tongue for cooperation with the body and provided with a slot for the reception of the comb teeth, and a hinge structure connecting the tongue with the body at one end, such structure comprising a member on the body for the reception and 45 hinging of the tongue and upstanding from the body, thereby placing such end at a substantial distance above the body to give suitable clearance to the hinged end of the tongue; said tongue, closely adjacent said 50 end, being downset toward the body, out of the tongue's general shape over all, thereby to overcome the spacing effect of said upstanding hinge member along the major portion of the length of the tongue to thereby 55 bring the tongue into intimately close holding 60 relation to said body, despite the said hinging clearance.

4. In a barrette, a body carrying comb teeth therealong, a tongue for cooperation with the body, and provided with a slot for

the reception of the comb teeth, a hinge structure connecting the tongue with the body at one end, and a fastening means for the tongue member and body at the other end, such fastening means comprising an upturned end portion of said body to thereby present a spaced-standard structure on the body for the reception of the tongue, the immediately cooperating parts presenting a shank-and-socket structure, and such hinge 70 structure comprising a member on the body for the reception and hinging of the tongue and upstanding from the body, thereby placing such end at a substantial distance above the body to give suitable clearance to the 75 hinged end of the tongue, said tongue, closely adjacent said end, being downset toward the body, out of the tongue's general shape over all, thereby to overcome the spacing effect of said upstanding hinge member along the 80 major portion of the length of the tongue to thereby bring the tongue into intimately close holding relation to said body, despite the said hinging clearance.

In testimony whereof I affix my signature. 85
JOHN B. RICHARD.
